FIG. 4

INVENTOR
J. H. MOLTHAN,
BY
Milton S. Graudalski,
ATTORNEY

UNITED STATES PATENT OFFICE.

JOHN H. MOLTHAN, OF CLEAR LAKE TOWNSHIP, DEUEL COUNTY, SOUTH DAKOTA.

LANTERN-BAIL.

1,358,385.

Specification of Letters Patent.

Patented Nov. 9, 1920.

Application filed January 11, 1919. Serial No. 270,721.

To all whom it may concern:

Be it known that I, JOHN H. MOLTHAN, a citizen of the United States, and a resident of Clear Lake township, in the county 5 of Deuel and State of South Dakota, have invented certain new and useful Improvements in Lantern-Bails, of which the following is a specification.

The invention aims, primarily, to provide 10 a lantern-bail differing from the familiar lantern-bail in that it has no U-shaped loop through which the carrier's arm is inserted, but in lieu thereof is formed with a hook which may be conveniently hooked over the 15 arm, or other projection, or engaged on the surface of a ledge to support the lantern.

Furthermore, the invention contemplates 20 an improved lantern-bail so constructed as to be held substantially upright to be conveniently grasped by the carrier when the lantern is setting on its base, and yet permit relative oscillation between the lantern and its bail.

Still another object of the invention is the 25 production of a lantern-bail, inexpensive and simple in construction, and adapted to be readily and securely applied to a lantern.

With these and other objects in view, the invention, consisting in the construction, combination and novel arrangement of parts, will be readily understood from the following description, reference being had to the accompanying drawings, which form a part of this application, and in which like characters of reference indicate corresponding parts throughout the several views, of which,—

Figure 1 is a fragmentary front elevation of a lantern equipped with the preferred embodiment of the invention;

Fig. 2 is a side elevation of the same with the bail tilted;

Fig. 3 is a perspective view of the bail; and

Fig. 4 is an enlarged side elevation of the hook terminal.

Although I have illustrated and herein-after described the preferred embodiment of the invention, I would not be understood as being limited to the specific structure chosen for illustration, for various alterations and modifications may be made in the details of construction and arrangement of parts without departing from the spirit and

scope of the invention as defined in the appended claims. 55

Referring, now, to the illustrations, the lantern illustrated includes the familiar tubular frame uprights, 5, provided in their remote sides with openings, 6, to receive the 60 bail terminals.

The bail consists, preferably, of a single piece of wire folded at its approximate center and twisted upon itself for a portion of its length, as at 7, the said twisted portion 65 being curved to form a hook, the folded end of the hook being formed with a depending eye, 8, the lower edge of which is preferably beveled to provide a comparatively sharp edge, 9. The said eye is disposed in a plane 70 at substantially right-angles to the plane of the hook.

The untwisted portions of the wire are bent laterally to the plane of the hook, and in opposite directions, as at 10, then inwardly and downwardly a distance, as at 11, then declined outwardly, as at 12, then formed with portions, 13, extending substantially directly downwardly adjacent the frame members, 5. The lower ends of the 80 portions, 13, are formed with eyes, 14, and their extreme end portions are extended inwardly, as at 15, to enter the openings, 6. One of said inwardly-extending portions, 15, is provided with a depending arm, 16. 85

In affixing the bail, the arm, 16, is first inserted through one of the openings, 6, and the bail then so tilted as to lead the adjacent portion, 15, into the opening. The other leg of the bail is then sprung outwardly to 90 permit introduction of its portion, 15, into the other opening. The short off-set portions, 11, in the legs of the bail, increase the tension of the legs to hold the eyes, 14, firmly against the lantern frame to prevent 95 displacement of the bail therefrom. The arm, 16, is of sufficient length to engage the front and rear walls of the inclosing frame member, 5, according as when the bail is tilted rearwardly or forwardly, thereby 100 holding the bail in an upwardly-extending position to be conveniently grasped.

The bail may be conveniently hooked over a person's arm, or hung on any suitable member; or the eye of the hook may be 105 engaged by a nail or pin in an upright support.

If desired, the point of the hook may be

engaged on a flat surface, represented by the dotted line in Fig. 2, the beveled edge of the eye preventing displacement of the hook from such surface.

5 The parts are so constructed and related that the bail may be tilted sufficiently to bring the point of the hook over the center of gravity of the lantern, as apparent in Fig. 2.

10 Having thus described my invention, what I claim as new and desire to secure by Letters Patent of the United States, is,—

15 1. A bail for a lantern having upright tubular side members provided with openings in their remote sides, comprising a carrying member, legs depending therefrom, the legs being formed adjacent their free end portions with approximately circular loops to engage the side members, the free 20 end portions of the legs being extended inwardly to enter said openings, whereby the

bail is pivoted to the lantern to permit relative oscillation between the bail and lantern, and permit tilting of the bail, and an arm on one of said extended portions, engageable with the wall of the adjacent tubular member, to limit such oscillation and retain the bail in an inclined position when the lantern rests on its base.

2. A bail for a lantern, comprising a carrying-hook, means thereon adapted to be pivoted to a lantern, the free end portion of the hook being downwardly-extended, and an eye formed on said free end portion, adapted to receive a supporting pin, the lower edge of the eye being sharpened for engagement with a flat horizontal surface to support the lantern and prevent displacement of the hook from such surface.

35 In testimony whereof I have hereunto set my hand this 23rd day of November, 1918.

JNO. H. MOLTHAN.
